UNITED STATES PATENT OFFICE.

GEORGE R. LAYMAN, OF LINCOLN, ILLINOIS.

ELEVATOR.

No. 809,117.

Specification of Letters Patent.

Patented Jan. 2, 1906.

Application filed July 8, 1905. Serial No. 268,792.

To all whom it may concern:

Be it known that I, GEORGE R. LAYMAN, a citizen of the United States, residing at Lincoln, in the county of Logan and State of Illinois, have invented certain Improvements in Elevators, of which the following is a specification.

This invention is an improvement in elevators, and relates more especially to that class of elevators which are used in mine-shafts primarily for the purpose of raising and lowering the cars by which the material is carried from the mine.

The principal objects of the invention are to provide a mine elevator or cage which shall be simple in construction, strong and durable, will greatly facilitate the operation of loading the cars thereon and unloading them therefrom, and will provide against serious accident in case the hoisting and lowering cable should break.

Other objects and advantages of the invention will hereinafter appear and the novel features of construction specifically pointed out in the claims.

In the accompanying drawings, which form a part of this specification, Figure 1 is a front elevation of an elevator or mine-cage constructed in accordance with my invention. Fig. 2 is a side elevation, the near shaft-beam and one of the side pieces of the cage being broken away to show the construction of the pivoted platform and parts carried thereby. Fig. 3 is a sectional view through the upper corner of the cage on the line 3 3 of Fig. 1. Fig. 4 is a transverse sectional view through the upper part of the cage on the line 4 4 of Fig. 1. Fig. 5 is a detail view of one of the safety-catches. Fig. 6 is a detail view of the locking-dogs for holding the car upon the pivoted platform. Fig. 7 is a detail view of one of the trip-levers for operating the locking-dogs.

Like letters of reference indicate like parts in all the views of the drawings.

My improved mine-cage is adapted to operate in a shaft provided with the usual vertical beams or uprights A A, suitably supported at opposite sides of the shaft, and which beams or uprights form the tracks or guides on which the elevator runs.

In constructing the cage in accordance with my invention I provide an upper pair of horizontal beams B B, forming the top of the cage, and a similar pair of beams B' B', forming the bottom of said cage, and connect said

upper and lower beams together by straight metal plates or flat bars C. The upper beams, as well as the lower, are spaced apart and are securely held in their relative positions by means of rectangular castings c, interposed between said beams near the opposite ends thereof and bolted thereto, as shown in Fig. 3. The beams are spaced apart to receive the uprights A of the shaft between the ends thereof, and as the connecting-plates or flat bars C, which form the sides of the cage, are attached to the ends of said beams they are disposed at the opposite sides of the uprights. Wear-plates c' in the form of angle-plates are bolted in place between the ends of the beams B B and B' B', as indicated in Fig. 3, and embrace the shaft-beams or uprights A. It will be noted that the plates or flat bars C are secured to the upper and lower beams of the cage by corner-braces or angle-plates c² and c³, the latter serving, with extensions c⁴ of said flat bars, to form the means of connection for the hoisting and lowering devices hereinafter mentioned; also, that the lower ends of the plates or flat bars C are extended under the lower beams B' to strengthen the connection at this point.

The parts described combine to produce a very strong and durable cage which will slide freely in the shaft upon and between the beams or uprights A and is of light construction consistently with the required strength, such cage being designed to support and carry the pivoted platform hereinafter described.

The elevator connections for the hoisting and lowering cable comprise the chains d, extending from the brackets c³ c⁴ and attached to a spreader-plate d', the latter carrying the eyebolt d², to which the cable d³ is attached. The eyebolt has the usual compression-spring d⁴ interposed between the nut-held washer d⁵ and aforesaid spreader-plate d'. This is one of the usual forms of connection.

Mounted upon the lower beams B' of the cage are bearing-blocks e e, in which is journaled a rock - shaft f, adapted to pivotally support the platform G of the cage. The platform is made up in any suitable manner, in the present instance of the horizontal beams g and connecting cross-beams g', and upon said platform are secured the track-rails h, upon which the cars run. The platform is supported from the rock-shaft f by means of triangular plates I, having outwardly-projecting flanges i at their upper ends by which they are secured to said plat-

form, such connection being reinforced by means of angle-bars i' , as shown in Fig. 1. The triangular plates I are reinforced at their lower ends, where they are fixed to the shaft, 5 by means of plates i^2 . This particular manner of supporting the platform permits the same to be swung or tilted at either side of the cage, so as to facilitate the discharge of the contents of the car at upper end of the 10 mine-shaft, and in order to support the platform horizontally during the travel of the cage in the shaft said platform is provided with shoes j , secured in pairs at opposite sides thereof and disposed to travel at opposite 15 sides of the beams or uprights A . To permit of the tilting movement of the platform, the beams or uprights A of the mine-shaft are cut away at their inner sides, as at a , whereby the shoes may pass the beams, 20 the beams or uprights being cut away for the purpose only at such points where the cage stops to take on and let off cars.

To hold the cars stationary on the platform during the travel of the cage in the 25 shaft and at the dumping-point, a pair of locking-dogs M are pivotally supported in the platform and so located that the same will be swung automatically to engage the wheels of the car when the elevator leaves 30 the bottom landing. These dogs each consist of a bar fixed at its lower end on a shaft m , bent forwardly at an angle intermediately, as at m' , and bifurcated at its upper end to provide the oppositely-curved members m^2 m^3 , which latter engage the inclined portion of the periphery of the wheels o of the car, passing in between the wheels at opposite sides of the car. The dogs are adapted to swing away from the car in disengaging 35 the wheels and are operated in this direction by means of trip-levers N , fixed on the opposite ends of the shafts m and extending toward the center of the platform parallel with the ends thereof, said trip-levers having outwardly-projecting engaging members n , by 40 which they are operated automatically by contact with bottom landing. These locking-dogs are normally brought to an upright position for engaging the car-wheels by means 45 of a compression-spring s , attached thereto and extending therebetween, and in this latter position of the dogs the free ends of the trip-levers are downwardly inclined, as shown in Figs. 1 and 2 of the drawings.

50 I provide the cage with an automatic safety device for arresting its fall in case there should be a break in the hoisting and lowering cable or the machinery operating the same. For this purpose safety-catches p are attached to the upper part of the elevator-frame and disposed at opposite sides of the beams or uprights A , so as to engage the latter and hold the cage suspended thereby. These catches are fixed on shafts p' , the 55 latter having bearings in brackets q , attached

to the beams B and at their ends in the corner-braces c^2 , (see Fig. 5,) such bearings being at opposite sides of the catches, so as to firmly support the same. The shafts p' are provided with outwardly-projecting fixed 70 arms p^2 , by which they are connected to a transverse rod p^3 , to which latter the operating-rod p^4 is attached. The operating-rod is connected by a chain p^5 and interposed spring p^6 to the spreader-plate d' 75 of the cage connections for the hoisting and lowering apparatus. There is also a helical spring p^7 , which encircles the operating-rod p^4 and is interposed between the transverse rod p^3 and a bearing-plate b , attached to the 80 beams B B , said bearing-plate also serving as a guide for the operating-rod. It will be noted that the tendency of the spring p^7 is to depress the rod p^3 , and consequently move the catches into engagement with the uprights, and that the connection of the operating-rod with the hoisting and lowering device is such that when the elevator is suspended from said latter device the catches will be out of engagement with the uprights. 85 In this manner when the draft on the operating-rod is released—for instance, in case the hoisting and lowering cable breaks—the spring p^7 will depress the rod p^3 , and the latter being connected to the transverse rods p' 90 will turn the latter to bring the catches into engagement with the uprights A of the mine-shaft, the engagement being such as to support the cage against falling. The interposed spring p^6 permits the safety device to 95 be operated manually by drawing upon the pull-cords v .

The safety-catches p are in the shape of cams having the engaging projections or members p^8 and p^9 , the member p^8 being bifurcated to provide points or spurs, while the member p^9 is thicker and provided with a straight edge, so as not to penetrate the beam to any great extent. The member p^8 is in advance of the member p^9 , whereby the 100 points of the former will when the catches or cams are swung against the beams penetrate the beam and bring the other or stronger member against the same to quickly and effectually stop the descent of the cage. 105

From the foregoing it will be readily seen that I provide a mine-cage which is extremely simple in construction and operation, is strongly built, will run freely and smoothly in the shaft, will facilitate the handling of the cars, and will prevent serious accident in case of a break or disarrangement of the hoisting and lowering apparatus. 110

Having thus described my invention, what I claim as new, and desire to secure by Letters Patent, is—

1. In a mine-cage, the combination with the uprights or guide-rails of the elevator-shaft having passage-ways therein, of the cage, a platform pivoted therein, vertically- 115

disposed triangular plates supporting the platform, a rock-shaft to which the triangular plates are fixed and forming a pivot for said plates by which the platform may be tilted, shoes at the sides of the platform adapted to slide on the uprights and pass through the passage-ways thereof when the platform is tilted, dogs pivoted in the platform and adapted to engage the wheels of a car run thereon, a spring connecting the dogs to hold them upright or normally in engagement with such wheels, and operating-levers connected to the dogs for releasing them, substantially as shown and described.

15 2. In a mine-cage, the combination with the cage, of a platform pivoted therein, dogs pivoted in the platform and adapted to engage the wheels of a car run thereon, said dogs comprising a bar bifurcated at its upper

or free end to provide oppositely-curved engaging members, shafts to which said dogs are fixed and extending longitudinally under the platform, levers attached to the shafts near the ends thereof and projecting toward the center of the platform at opposite ends of the latter, arms projecting outwardly at the free ends of the levers, and a spring adapted to hold the dogs normally upright with the levers at a downward inclination, substantially as shown and for the purpose set forth.

20 25 30 In testimony whereof I have signed my name to this specification in the presence of two subscribing witnesses.

GEORGE R. LAYMAN.
